[57] CLAIM

The ornamental design for a record clamp, substantially as shown.

DESCRIPTION

FIG. 1 is a perspective view of the record clamp showing my new design;

FIG. 2 is a top plan view of the record clamp;

FIG. 3 is a front elevational view of the clamp;

FIG. 4 is a left elevational view showing one side of the clamp;

FIG. 5 is a right elevational view showing a side opposite the one side of FIG. 4;

FIG. 6 is a rear elevational view of the clamp; and

FIG. 7 is a bottom plan view of the clamp.

FIGS. 2-7 are all on a reduced scale.

Fig. 1.Fig. 2.Fig. 4.Fig. 3.Fig. 5.Fig. 6.Fig. 7.
